US00D597205S

(12) **United States Design Patent**
Koch

(10) **Patent No.:** **US D597,205 S**
(45) **Date of Patent:** **** Jul. 28, 2009**

(54) **HANDLE FOR ENDOSCOPE STIFFENING DEVICE**

(75) Inventor: **Drake Lansdon Koch**, Kansas City, MO (US)

(73) Assignee: **Zutron Medical, L.L.C.**, Kansas City, MO (US)

(**) Term: **14 Years**

(21) Appl. No.: **29/322,361**

(22) Filed: **Aug. 1, 2008**

Related U.S. Application Data

(63) Continuation of application No. 11/159,566, filed on Jun. 22, 2005, which is a continuation-in-part of application No. 11/021,524, filed on Dec. 22, 2004, now abandoned.

CLAIM

The ornamental design for a handle for endoscope stiffening device, as shown and described.

DESCRIPTION

FIG. 1 is a top and side perspective view of a handle for endoscope stiffening device, showing my new design;

FIG. 2 is a top and side perspective view of a handle for endoscope stiffening device;

FIG. 3 is a top and side perspective view thereof, shown rotated 180 degrees;

FIG. 4 is a top and side perspective view thereof, shown rotated 90 degrees;

FIG. 5 is a top and side perspective view thereof, shown rotated 180 degrees;

FIG. 6 is a top plan view thereof;

FIG. 7 is a bottom plan view thereof;

FIG. 8 is a side elevational view thereof; and,

FIG. 9 is a side elevational view thereof, shown rotated 180 degrees.

The broken lines shown in the FIG. 1 drawing view are for environmental purposes only and form no part of the claimed design.
